UNITED STATES PATENT OFFICE.

FRANKLIN W. BROOKS, OF NEW YORK, N. Y.

IMPROVEMENT IN SEALING LOCKS.

Specification forming part of Letters Patent No. 99,831, dated February 15, 1870.

To all whom it may concern:

Be it known that I, FRANKLIN W. BROOKS, of the city, county and State of New York, have invented a new and useful Improvement in Sealing-Locks, which is described as follows:

My invention relates primarily to the class of seal-padlocks which is commonly used in the bonded warehouses of the United States, the same having the key-hole protected by a seal of paper or analogous material held in position by a hinged plate which is provided with a suitable key-hole, and when shut down upon the paper seal is there held by a spring-catch within the lock, which can only be retracted by the same action of the key which retracts the main bolt or catch from the shackle of the lock, so that the act of unlocking releases the seal-plate, and so admits of the seal being taken out and replaced by a new one, but as the seal before placed in position has been destroyed by the passage of the key, and cannot be reproduced or duplicated by any unauthorized party, the fact of the lock having been opened cannot be concealed.

These locks as now commonly made and used fail to afford the security intended by reason of the manner in which the seal-plate is made and applied. The heel (or hinged end) of the said plate can without much difficulty be released from its attaching-pin and raised sufficiently to admit of withdrawing the paper seal or pushing it out of the way, in either of which cases a key or pick can be introduced through the key-hole to open the lock without piercing the seal, so that when the lock has been relocked the seal and its plate can be replaced, and detection thus avoided.

To prevent the possibility of thus tampering with the lock by the surreptitious removal of the seal is the object of my invention, and to this end I prefer to form the seal-plate of frangible or inflexible metal or other material, and the seal of variegated glass which cannot be bent, and, if broken, cannot be duplicated, so that even if the hinge end were released it could not be bent up and replaced without detection, and I construct the hinge not with an exposed pintle extending completely through the seal-case, so as to admit of being punched out as in the locks now used, but I form it preferably with two studs made in one solid piece with the hinged plate, and upon the heel

thereof, so that the said plate must be inserted from the rear before the lock is put together, and cannot be removed without taking it to pieces. The studs in this case fit in recesses in the seal-case or face-plate of the lock; but the same result may be effected by screwing pins from both sides into holes which do not go entirely through, and the head or outer end of the screws being cut off flush and subsequently clinched, any attempt to remove them will inevitably be detected.

In the accompanying drawings, Figure 1 is a front view of a seal-padlock, illustrating my invention. Fig. 2 represents a transverse section of the same at *x x*, Fig. 1. Fig. 3 is an interior view of the seal-plate and its case. Fig. 4 represents a longitudinal section at *y y*, Fig. 1. Fig. 5 is a face view, partly in section, illustrating a modification in the manner of securing the hinge-pintle. Fig. 6 is a view of the inside of the face-plate of the lock as made in one piece with the seal-case, showing the aperture made for the introduction of the seal-plate and the said plate in position. Fig. 7 represents a longitudinal section of the same parts at *z z*, Fig. 6. Fig. 8 is a perspective view of the lock-plate with seal-case attached, showing a seal of variegated glass within a metallic frame. Fig. 9 represents a longitudinal section of the seal and its frame or plate.

Like letters of reference refer to corresponding parts in the several views.

My improved lock in its general construction may be similar to those in common use of the description referred to, and hence the internal mechanism and the holding shackle do not require description, and are not represented in the drawings.

A represents the face-plate of the lock, and B the seal-case which may be formed in one piece therewith or permanently attached thereto by soldering or other means, the seal-plate C being applied between it and the plate A with the pivot-studs *c c*, which are formed in one piece with the plate, fitted in recesses prepared for their reception in the seal-case B. As will be seen in Figs. 2 and 3, these recesses do not extend to the outside of the case.

D represents the customary stud upon the seal-plate, with which a spring-catch within the lock engages to hold the said plate down.

E is the key-hole, which is made of corre-

sponding shape in the lock-plate and seal-plate, as is usual.

In Fig. 5 is shown an equivalent mode of making a permanent hinge which cannot be detached without subsequent detection. This is done by means of screws $c'c'$, which, after being screwed firmly into corresponding threaded sockets in the seal-case B, are cut off flush, and clinched on the outside, so that they cannot be withdrawn. Their plain inner ends fit loosely within sockets in the seal-plate, so that the latter may turn freely upon them.

In Figs. 6 and 7 the seal-case B is shown as made in one piece with the lock-plate A, an aperture, a , being in the plate to admit of the insertion of the seal-plate C endwise from the back or inside of the face-plate A before the latter is fixed in position on the lock.

By making the seal of variegated glass its duplication may be rendered impossible, so that it cannot be removed and replaced by another

without detection. This form of the invention is illustrated in Figs. 8 and 9, where the glass seal S is represented as set within a hinged metallic frame, C', so formed as to retain it securely when locked. This seal, being of variegated glass, which cannot be successfully imitated, may be represented by photography or other means, and the representation, being retained by the authorized party, will enable him to verify the seal found in position at any time.

I claim—

So arranging the glass seal S under the plate C or C', constructed as described and attached to the lock by the permanent hinge c or c' , as that the seal must be broken before the key can be inserted, substantially as set forth.

FRANKLIN W. BROOKS.
